UNITED STATES PATENT OFFICE.

JAMES FOULIS AND DAVID FOULIS, OF WHEATON, ILLINOIS.

DESIGN FOR A GOLF-BALL.

SPECIFICATION forming part of Design No. 30,378, dated March 21, 1899.

Application filed January 30, 1899. Serial No. 703,900. Term of patent 7 years.

To all whom it may concern:

Be it known that we, JAMES FOULIS and DAVID FOULIS, subjects of the Queen of Great Britain, (but having declared our intention of becoming citizens of the United States,) residing at Wheaton, in the county of Du Page and State of Illinois, have invented a new and useful Design for Golf-Balls, reference being had to the accompanying drawing, forming a part hereof.

The accompanying drawing represents an elevation of a golf-ball embodying our design.

The leading feature of our design comprises a spherical golf-ball provided with a series of encircling stars on its outer surface.

A is the spherical golf-ball, and B the series of encircling pointed stars on its outer surface, the whole presenting to the eye a harmonious and ornate figure, as shown in the accompanying drawing.
